US00D556204S

(12) **United States Design Patent** (10) **Patent No.:** **US D556,204 S**
(45) **Date of Patent:** **** Nov. 27, 2007**

(54) **FILLER PANEL WITH INTEGRATED DUST COVER**

(75) Inventors: **Andrew Tosh**, Maynard, MA (US); **Lisa Marie Surowiec**, Beverly, MA (US); **Christopher H. Frank**, San Jose, CA (US)

(73) Assignee: **Sun Microsystems, Inc.**, Santa Clara, CA (US)

(**) Term: **14 Years**

(21) Appl. No.: **29/259,825**

(22) Filed: **May 16, 2006**

(51) **LOC (8) Cl.** **14-02**

(52) **U.S. Cl.** **D14/439**

(58) **Field of Classification Search** D14/363, D14/367, 432-439, 489; D13/146, 147, D13/120, 133, 199; 312/223.1, 223.2; 439/159, 439/160, 433, 630, 65, 295, 441, 660, 862, 439/152, 607-610, 131, 299, 300, 345, 372, 439/928.1; 361/685, 727; 200/51.09

(57) **CLAIM**

The ornamental design for a filler panel with integrated dust cover, as shown and described.

DESCRIPTION

FIG. 1 shows a front perspective view of the design according to the invention.

FIG. 2 shows a rear perspective view of the design according to the invention.

FIG. 3 shows a top view of the design according to the invention.

FIG. 4 shows a front view of the design according to the invention.

FIG. 5 shows left side view of the design according to the invention; and,

FIG. 6 shows a right side view of the design according to the invention.
